UNITED STATES PATENT OFFICE.

CHARLES J. AHRENFELDT, OF NEW YORK, N. Y.

DESIGN FOR A COVERED DISH.

SPECIFICATION forming part of Design No. 24,376, dated June 11, 1895.

Application filed January 15, 1895. Serial No. 535,035. Term of patent 7 years.

To all whom it may concern:

Be it known that I, CHARLES J. AHRENFELDT, a citizen of the United States, residing at New York city, county and State of New York, have invented and produced a new and original Design for a Covered Dish, of which the following is a specification, reference being had to the accompanying drawings, forming a part thereof.

10 Figure 1 is a perspective view of a dish, showing my design, with the cover removed. Fig. 2 is a top view of said cover.

15 The leading feature of my design consists of a covered dish, the handles of which are provided with an ornamentation representing a sheaf of leaves bound together by cords or ribbons running around, as shown in the accompanying drawings.

A is the body of the dish.

B, B are the handles.

C is the cover of the dish, and D is the handle of the cover.

The ornamentation of the handles B, B and C, represents a fasces or sheaf of leaves bound together by narrow bandages, passing around it in opposite directions.

What I claim is—

The design for a covered dish substantially as herein shown and described.

CHARLES J. AHRENFELDT.
